UNITED STATES PATENT OFFICE.

JAMES MEANS, OF BOSTON, MASSACHUSETTS.

APPARATUS FOR LAUNCHING FLYING-MACHINES.

No. 922,711.

Specification of Letters Patent.

Patented May 25, 1909.

Application filed August 25, 1908. Serial No. 450,171.

To all whom it may concern:

Be it known that I, JAMES MEANS, a citizen of the United States, and a resident of Boston, in the county of Suffolk and State 5 of Massachusetts, have invented a new and useful Improvement in Apparatus for Launching Flying-Machines, of which the following is a specification.

My invention relates to apparatus for 10 launching flying machines.

In a flying machine of the aeroplane type a certain high initial velocity in the direction opposite to that of the wind is desirable for soaring, and this velocity which 15 varies according to conditions is best imparted to the machine by means extraneous thereto, so that the weight of the machine may be a minimum.

The object of my invention is to provide 20 a simple and efficient apparatus for launching flying machines whereby any desired initial velocity may be imparted to the machine to be launched in a direction toward any point of the compass.

With this object in view my invention 25 consists in a table, preferably rotatable, and fluid-pressure-controlled means whereby the desired initial velocity may be imparted either directly to the flying machine or to a 30 truck or other device carrying the same. The particular fluid - pressure - controlled mechanism which I prefer to employ consists in a cylinder provided with means for evacuating the same to any desired degree, 35 and a piston adapted to be acted upon by atmospheric pressure against the vacuum created in the cylinder; but it will be understood that I do not limit myself specifically to the fluid-pressure-controlled mechanism 40 hereinafter described, inasmuch as other fluid-pressure-controlled mechanisms may be employed, such for example as one operated by gas under high pressure.

In the drawings which accompany and 45 form a part of this specification Figure 1 is a plan view and Fig. 2 is a central section of one embodiment of my invention.

In that embodiment of my invention selected for illustration and shown in the 50 accompanying drawings, A represents a table of suitable dimensions supported by the columns H on the base W, which in turn may be supported by ball-bearings or other suitable friction-reducing devices on 55 the standard Q. The axle O which is rigidly secured to or integral with the base W is

inclosed within the journal P so that said base with its super-imposed table may with minimum effort be rotated about the center of said journal.

The table is provided with suitable guideways B which may be single or double rails, tracks or grooves upon which the device C may be supported and by which said device may be guided. As shown, the members B 60 are guide bars and the device C which may be a truck or sled carrying a flying machine, or which may be the flying machine itself, is prevented from leaving the guideways B when the truck is in motion by overhanging 65 edges C'. It will be understood, however, that any suitable means may be employed for maintaining the truck C on the guideways B. The table may be provided with a centrally arranged slot disposed above the 70 cable D which passes around the grooved pulley E and which may be driven at a high velocity by the fluid-pressure-controlled mechanism hereinafter described. The rearward end of said cable is provided with suitable self-detaching device for temporarily 75 connecting said cable with the truck C. As shown, this device consists in a socket F secured to the under side of the truck and open on one side so that the ball G on the end of 80 the cable may be retained within the socket so long as the cable exerts a forward pull on the same. However, as soon as the sled reaches a point near the end of the guideways B, the pull of the cable is downward and 85 the ball will drop out of the socket thereby disengaging the cable from the device C. This device, if it be the flying machine to be launched, will enter upon free flight and if it be a truck carrying said machine it will 90 merely fall to the ground in front of the launching device.

Arranged beneath the table A and preferably supported by the base W is a cylinder T of suitable length carrying a piston I, which 100 preferably is a double piston as shown and provided at its inner end with the spring buffer or other suitable cushioning device J and with a pressure gage N. Any suitable air pump K which may be supported by the 105 base W is connected with the cylinder T by the pipe L provided with the valve M. It will be understood, however, that the cylinder T may be evacuated by any suitable mechanism extraneous to the launching device.

R is a brake coöperating with the drum

R' of the pulley E and actuated in any suitable manner, as by the lever S. The trip U operated by the bell-crank lever V may be employed as shown for restraining the rearward movement of the piston I while the cylinder is being evacuated.

The operation is as follows: The sled or flying machine C is placed in the position shown in the drawings at or near one end of 13 the guideways B, and is connected with the cable D by the ball and socket joint GF. The trip U is adjusted to prevent any rearward movement of the piston. The air pump K is put in operation to exhaust the cylinder T to the desired degree as indicated by the 15 gage N. The turntable is, or previously has been, oriented so that the guideways have a position parallel to the direction desired in flight. The brake R is then strongly applied 20 and the piston I released by a movement of the lever V throwing the trip U out of the cylinder, whereupon the pressure of the atmosphere upon the piston forces the same through the cylinder to the buffer J, its 25 velocity and consequently that of the device C being regulated by the brake R. In this manner, the initial velocity desired for launching the flying machine is imparted thereto in the desired direction, and at a 30 point near the forward end of the guideways the cable is automatically released from said machine thereby allowing the same to enter upon free flight.

One of the advantages of my invention lies 35 in its suitability to those military operations where portability must be considered, this portability in part arising from the fact that the cylinder T when evacuated is a reservoir of energy in which the cumulative effect of 40 a comparatively small motor-actuated air pump may be stored between launchings.

It will be obvious that between the piston and the device C any suitable multiplying 45 device may be used in case it should be found desirable to increase the area of the piston and diminish the length of its stroke.

It will be understood that many modifications may be made in the apparatus shown 50 in the drawings and hereinbefore described without departing from the spirit of my invention.

I claim:

1. In an apparatus for launching flying 55 machines, the combination, with a table, of fluid-pressure-controlled mechanism for imparting forward motion to the machine to be launched.

2. In an apparatus for launching flying 60 machines, the combination, with a table, of fluid-pressure-controlled mechanism for imparting a variable initial velocity to the machine to be launched.

3. In an apparatus for launching flying 65 machines, the combination, with a revolute table, of fluid-pressure-controlled mechan-

ism for imparting forward motion to the machine to be launched.

4. In an apparatus for launching flying machines, the combination, with a revolute 70 table, of fluid-pressure-controlled mechanism for imparting a variable initial velocity to the machine to be launched.

5. In an apparatus for launching flying machines, the combination, with a table, of a 75 cylinder containing a piston, means for evacuating said cylinder and means operatively connecting said piston with the machine to be launched.

6. In an apparatus for launching flying machines, the combination, with a revolute 80 table, of a cylinder containing a piston, means for evacuating said cylinder and means operatively connecting said piston with the machine to be launched.

7. In an apparatus for launching flying 85 machines, the combination, with a table, of a cylinder containing a piston, means for evacuating said cylinder and self-detaching means operatively connecting said piston with the machine to be launched. 90

8. In an apparatus for launching flying machines, the combination, with a table, of a cylinder containing a piston, means for evacuating said cylinder, and a cable connecting 95 said piston with the machine to be launched. 95

9. In an apparatus for launching flying machines, the combination, with a table, of a cylinder containing a piston, means for evacuating the cylinder, a cable connecting said piston with the machine to be launched, and 100 means for automatically detaching said cable from said machine at a point near the forward end of said table.

10. In an apparatus for launching flying machines, the combination, with a table, of a 105 cylinder containing a piston, means for evacuating the cylinder, means for restraining said piston during the evacuation of said cylinder and means operatively connecting said piston with the machine to be launched. 110

11. In an apparatus for launching flying machines, the combination, with a table, of a cylinder containing a piston, means for evacuating the cylinder, means operatively connecting said piston with the machine to be 115 launched and means for regulating the velocity of said piston during the launching operation.

12. In an apparatus for launching flying machines, the combination, with a table, of 120 guideways thereon constructed to support the machine to be launched, a cylinder containing a piston, means for evacuating said cylinder and means operatively connecting said piston with the machine to be launched, 125 whereby the latter may be propelled along said guideways.

13. In an apparatus for launching flying machines, the combination, with a table, of fluid-pressure-controlled mechanism extra- 130

neous to the machine to be launched for imparting forward motion thereto.

14. In an apparatus for launching flying machines, the combination, with a revolute table, of fluid-pressure-controlled mechanism extraneous to the machine to be launched for imparting forward motion thereto.

In testimony whereof, I have hereunto subscribed my name this 24th day of Aug. 10 1908.

JAMES MEANS.
